REFRIGERATOR

James H. Ward, Jr., Niles, Mich., assignor, by
mesne assignments, to Tyler Fixture Corpora-
tion, a corporation of Michigan

Application April 17, 1936, Serial No. 74,868

5 Claims. (Cl. 312—116)

This invention relates to refrigeration, being more particularly concerned with a novel structure of refrigerator casing and of moisture collecting and evaporating apparatus within the casing, whereby a very complete, efficient and satisfactory refrigerator is provided at a marked decrease in cost. Furthermore, my construction has many desirable features not hitherto present in refrigerator constructions.

10 One of the primary objects of the present invention is to provide a refrigerator frame in the form of a casing which is made entirely of sheet metal, the parts thereof being readily formed into shape and assembled quickly and easily and 15 without the use of forms or jigs and connected by welding. The sheet metal frame is suitably covered at its inner side with heat insulating material at the inner side of which is an inner lining of sheet metal. The refrigerator is particularly adapted for commercial use in stores or the 20 like and is made so that the contents may be readily displayed through the front of the upper portion of the refrigerator case and removed therefrom at the opposite side.

25 The temperature within the refrigerator case is not to be excessively low whereby frost, ice or the like collects on the refrigerating coils and other interior parts of the casing. Instead, moisture only condenses upon the coils. One feature of my invention is concerned with a simple, practical and efficient method of evaporating this moisture whereby the space within the refrigerator casing maintains its good degree of humidity, thus avoiding what has heretofore been 30 one objection to so-called mechanical refrigeration.

35 As just explained the temperature within the refrigerator casing is not excessively low and in fact this temperature is not below freezing. This 40 is a very great advantage inasmuch as ice does not form upon the cooling coils and consequently defrosting is eliminated.

45 Along this same line the cooling coils are arranged so that the moisture which condenses thereon, this moisture being taken from the air, is rapidly reevaporated into the air and thus the proper degree of humidity is maintained within the refrigerator. The flow of air is controlled and regulated so that reevaporation of the 50 condensed moisture will be facilitated. The air is so controlled as to make it flow directly downwardly from the upper cooling coil and during this initial movement the air passes around the lower portion of the cooling coil and immediately above two spaced troughs into which the condens- 55

5 sate from the cooling coil has collected. This air, due to the shape of its passageways, gathers therein a part of the moisture which has condensed therefrom. Then flowing directly downwardly the air spreads out somewhat and impinges against and passes through the moisture which is dripping from the intermediate cooling coils. Here again the air absorbs additional moisture from the grid-like arrangement of the moisture collecting troughs.

10 The air now passes toward the bottom of the refrigerator where it again flows against and impinges the excess water on the bottom which is still unevaporated and again the air somewhat increases its humidity. The flow of the air is then 15 upwardly along either side of the refrigerator casing. This is a natural flow inasmuch as the walls of the refrigerator give off whatever heat is absorbed by the refrigerator.

20 Another very important advantage of my invention resides in the construction wherein the main frame is formed without any wooden members therein. This permits the frame construction, which is formed of flat sheet metal elements, to be sprayed with a priming coat of paint 25 and then baked in an oven whereby the paint is hardened to form its protective coating. By this construction, the parts are thoroughly protected. There is no wooden construction present which 30 obviously is advantageous.

35 Another advantage resides in my ornamental panel construction whereby the panels may be individually replaced whenever deemed necessary. For instance, should one of the sides of the refrigerator become damaged it is only necessary 40 to remove that particular side, this being easily accomplished, and then replace it by a new panel. Thus, the refrigerator is again of its original neat appearance. Only a minimum of 45 labor and expense is involved.

50 Another advantage resides in the particular construction of the outer lower portions of the several panels. These panels are indented and an ornamental strip is carried therein. This ornamental strip can be readily removed, being detachably fastened on by self-threading screws, whereby the case can be readily moved about without any injury resulting from the use of 55 prying bars which bars are usually used for this purpose. After the refrigerator case is in its desired position the ornamental panel members are attached in their respective positions thus completing the case and giving it a neat and finished appearance. Preferably, these ornamental panels are of a very dark color, such as black.

whereby they do not show minor injuries thereto.

Yet another very material advantage resides in my construction whereby the unitary glass unit is bodily removable from the case. Oftentimes, a glass may become broken in this unit or it may become defective for some other reason, and then replacement is made relatively easy by my novel construction. That is, the glass unit, consisting of a frame member with a plurality of glass panels sealed therein, can be readily withdrawn from the case and a new unit quickly and easily inserted. This new unit has been originally assembled at the factory in the dehydrated room and is in perfect condition. Furthermore, the installation of the new unit does not require skilled labor. Formerly, it was necessary to individually replace and reseal the several glass panels with the result that the humidity of the air at that particular time controlled the amount of humidity which was sealed between these glass panels. Obviously, this was objectionable inasmuch as there should be no humidity present whatsoever in the air between these glass panels.

Another feature of my invention which is very important lies in the construction of and concealment of the lighting fixtures whereby there will be no direct rays of light striking the customer in the face. This is accomplished in part by the frosted construction of the outer side of the outermost glass panel, this frosting extending downwardly to a point substantially below the overhanging portion of the top of the refrigerator case.

An understanding of the invention and of the structures for attaining the objects of the same may be had from the following description, taken in connection with the accompanying drawings, in which,

Fig. 1 is a perspective view of the refrigerator casing from the front and end thereof and before the finish or decorative panels and moldings have been applied thereto.

Fig. 2 is a similar perspective view at the rear of the casing.

Fig. 3 is an enlarged transverse vertical section therethrough.

Fig. 4 shows a perspective and in separated form the major portion of the elements which are used in building the outside sheet metal casing structure.

Fig. 5 is a fragmentary enlarged vertical longitudinal section taken at one end of the refrigerator casing.

Fig. 6 is an enlarged fragmentary section of the upper part of the construction shown in Fig. 5, illustrating the drain for moisture which may drip from the upper coils.

Fig. 7 is a transverse section through the upper refrigerating coil structure and the moisture collecting and draining pan therefor.

Fig. 8 is a perspective view showing the lower moisture collecting and drainage structure below the lower refrigerating coil.

Fig. 9 is a fragmentary transverse section therethrough, the section being taken longitudinally of the refrigerator.

Fig. 10 is a fragmentary perspective illustrating the end members of the moisture collecting and drainage structure shown in Figs. 8 and 9.

Fig. 11 is a fragmentary perspective and section illustrating the structure used in the assembly of the glass display frame of the refrigerator.

Fig. 12 is a horizontal section through one of

the doors to the lower compartment of the refrigerator.

Fig. 13 is a perspective view of the corner construction of the inner wood frame of said door.

Fig. 14 is a fragmentary perspective view of one end portion of the refrigerator with the finishing moldings and panels applied thereto.

Figs. 15 and 16 are, respectively transverse sections on the planes of lines 15—15 and 16—16 of Fig. 14.

Fig. 17 is a sectional view taken along the line 17—17 of Fig. 14.

Fig. 18 is a vertical sectional view through the lower part of the sliding doors illustrating a modified form of construction, and

Fig. 19 is a horizontal cross sectional view taken through one end of the unit glass panel.

Like reference characters refer to like parts in the different figures of the drawings.

Referring to Figs. 1 and 4, the outer structure of the refrigerator casing includes two ends of sheet metal each having a vertical body 1 from which flanges extend inwardly. At the front vertical edge of the body a flange 2 is turned inwardly connected with which is a similar flange 3 which extends upwardly and rearwardly, joining with a relatively short horizontal flange 4 at the top edge of the body 1. The flanges are thence continued around the body in a downwardly and rearwardly extending flange 5, a vertical flange 6 at the rear vertical edge of the body, and a horizontal lower flange 7 (Fig. 5) turned from the lower edge of the body 1 which terminates in an upturned lip 8.

The inner edge of the flange 3 described has the metal continued as an inwardly extending section 9 which parallels the body 1 and which terminates at its lower edge in a lip 10 extending in substantially the same direction as the flange 3. Neither of the parts 9 and 10 extend to the lower ends of the respective flanges 3 and 5 with which they are integrally connected but end a short distance therefrom, as shown.

The various flanges 2, 3, 4, 5, 6 and 7 are of a width substantially equal to the thickness of the heat insulating material which is used to prevent the passage of heat from the outside to the interior space of the refrigerator.

A front panel 12 of sheet metal is provided to extend between the two spaced apart end members of the outer sheet metal casing. At the lower horizontal edge of the panel 12 a flange 13 is turned inwardly which terminates in an upturned lip 14. At the upper edge a section 15 is turned to extend upwardly and inwardly at an angle to the vertical for a short distance and is then bent substantially at right angles, as at 16, and terminates in a downwardly and inwardly turned lip 17. The parts 16 and 17 are cut off for a distance at their end portions, as indicated in dotted lines in Fig. 4, whereby the remaining end portion of the panel 12 passes within the flange 2 previously described.

The flange 8 is cut away as shown whereby the flange 13 and its lip 14 may be inserted adjacent the bottom flange 7 of the end panel. The flanges 2 overlap the ends of the panel 12 and may be secured thereto by suitable welding, such as gas welding at the edges of the flanges 2.

A back panel 18 of sheet metal is provided to lie at the upper portion of and between the in-turned flanges 6 of the end members. The panel 18 at its lower edge has an inturned lip or flange 19; while at its upper edge, it is bent to extend upwardly and forwardly for a distance,

making the section 21, then inwardly to form a lip 22, and then termination in a downturned flange 23.

The section 21 lies back of the flange 5 and the section 18 lies back of the flanges 6. The end of this member 18 abuts against the inner face of the end panel 1, similar to the front panel 12, and these contacts automatically align these several members whereby true right angles are obtained therebetween. Welding maintains the several members together.

At the lower portion of the back of the casting a sheet metal rail is provided having a vertical web 24 from which a horizontal flange 25 extends at its lower edge terminating in an upturned lip 26. At the upper edge of the web 24 a shorter flange 27 is turned inwardly.

The rail just mentioned extends alongside of the flanges 6 and 7 and abuts the inner faces of the end members similarly to the panels 12 and 18, previously mentioned. The flange 8 is cut away, see Fig. 4, to permit this assembly. The rail is welded to the said flanges.

A sheet metal bottom 29 (Figs. 3 and 5) has a lip or flange 30 turned downwardly therefrom at its front and rear edges (Fig. 3), and has a lip 31 turned downwardly and terminating in a horizontal portion 31a at each end. The bottom is located between the ends, the front panel 12 and the rear lower rail 24. As shown in Figs. 3 and 5, the edges of the lips or flanges 30 rest upon the flanges 13 and 25, while the horizontal lip 31a at each end of the bottom 29 rests upon the horizontal flanges 7 at the lower edges of the end members. The horizontal flanges 31a may be welded or otherwise permanently secured to the flanges 7.

A wooden frame shown in dotted lines in Fig. 4 is used, comprising a lower horizontal rail 33, an upper rail 34 parallel to and spaced therefrom, with spaced apart vertical posts 35 extending between the lower and upper rails. This frame lies between the panel 18 and the lower rail described at the rear of the casing, the upper rail 34 lying immediately above the flange 19 and with the rear edge portions of the posts 35 notched to receive the flange 19. The lower rail 33 passes underneath the flange 27 and the rear lower edge portions of the posts 35 are notched to receive the flange 27.

A horizontal rail 32 of substantially the same cross section as the lower rail 33 is positioned directly beneath said rail 33 and lies on the bottom 29 as shown in Fig. 3. The ends of the several rails 32, 33 and 34 come to the edges of the flanges 6 so as to abut against the heat insulating material which is within the several flanges turned inwardly from the bodies 1 of the end members. The posts 35, closest to the ends of the casing, are spaced a short distance from the edges of the flanges 6. Vertical sheet metal panel members 36, each with an inturned flange 37 at one vertical edge thereof, and with upper and lower lips 38 turned inwardly from the upper and lower edges (Fig. 4), are used one at each end of the wooden frame described, each having a portion to be inserted within the adjacent flange 6 of the end members. The lips 38 pass above and below the rails 33 and 34 respectively, and the flange 37 passes inwardly alongside the end post 35. The end post 35 is notched to receive the lips 38.

Similarly, at the central portion of the frame a vertical panel 39 with a vertical flange 40 at each vertical edge and lips 41, is inserted so that

the lips 41 pass above and below the rails 33 and 34 respectively, and the flanges 40 pass to each side of posts 35, there being two of said posts relatively close together at the middle portion of the wooden frame. The posts are notched to receive the lips 41. This provides an open frame structure lined at its outer side with sheet metal, having two openings therein in which doors may be mounted for closing and opening the same as will be later described.

Likewise, there is a door opening at the upper rear portion of the refrigerator above the panel 18. This opening is of an elongated character and at each end thereof is a pan-like panel 39a having flanges turned inwardly around three edges thereof (Fig. 4). The extended flat portion lies interiorly and adjacent to the flange 5 and is welded thereto in any suitable manner.

The top of the outer metal casing is provided by an elongated panel 42 of sheet metal having projecting end portions 43 to pass underneath the top flanges 4 of the end members. Sections 44 and 45 extend downwardly and forwardly and thence downwardly and inwardly at its front edge and a section 47 extends downwardly at the rear edge terminating in an inturned flange 48 which in turn has an upwardly turned lip 49 at its edge as shown in Fig. 4. The projection portions 43, 44 and 47 are welded to the flanges of the end members and there is completed at the rear of the casing an upper opening for entrance into the casing. Also, there is provided at the front upper portion of the casing a front opening in which a glass assembly structure is placed, as later described, for display of meats or other merchandise which is carried in the upper portion of the refrigerator.

At the inner sides of the sheet metal outer members of the casing described, heat insulating material of well known composition is placed. For example, the bottom 29 is covered by a thickness 50 of such material, extending between the rails 32 and 33 to the insulating material 51 back of the front panel 12. These heat insulating members 50 and 51 at their ends abut against similar heat insulating material 52 which fills the spaces between the flanges extending from the bodies 1 of the ends. The end insulation is split as indicated by the dotted lines of Fig. 4.

Inside of the back panel 18 described is similar heat insulating material 53, see Fig. 3, resting upon the top bar 34 of the wood frame described and underneath the top in a thickness of heat insulating material 54.

The inside of the refrigerator casing is lined with sheet metal. Over the bottom insulating material 50 is a sheet metal plate 55 with upturned flanges 56 at its front edge and ends, while at its rear edge it is offset, as indicated at 51, so as to pass partly over the bar 33. Tacks extend through both the edge of member 57 and the edge or flange 27 of the rear lower rail of the case. Thus these members are separated whereby a heat loss is prevented. Immediately inside the front insulating material 51 is a vertical sheet metal plate 58 which passes inside of the flange 56 (Fig. 3) and extends upwardly a short distance above the heat insulating material 51. The ends have their heat insulating material 52 lined and covered by metal plates 59 and 60 coming inside the flange 56 as shown in Fig. 5.

The plate 60 has an offset portion extending over the upper portion of the plate 50. A sealing strip lies therebetween and screws hold these parts together.

5 At the top of the casing there is an inner lining 61 of sheet metal underneath the heat insulating material 54. This lining has downturned flanges 62 at its ends lying outside of the upper edges of the plate 60. See Fig. 6. This lining 10 also has a downwardly and rearwardly turned section 63 at its rear edge shaped as shown in Fig. 3. At its front edge is formed a vertical section 64 which is continued into two sections 65 and 66 (Fig. 3) shaped to conform to the lower 15 and rear sides of a horizontal bar 67 located at the front edge of the insulating material 54. At its upper side this bar 67 bears against the top-plate 42, being held in place by a substantially Z-shaped bar 68, one flange of which is welded 20 or otherwise permanently secured to the under-side of the plate 42. The other flange extends into a slot cut in the bar 67, as shown in Fig. 3.

A frame for the rear door opening at the upper portion of the case is provided including an upper 25 horizontal bar 69 and a lower horizontal bar 10 with vertical end bars connecting the same. The lower bar rests upon the insulating material 53 (Fig. 3) while the flanges 21 and 22 at the upper edge of the back plate 18 pass partly around and 30 connect with the lower bar 10 as illustrated. The flange 23 extends downwardly into a groove located in the top of bar 10. The inside of the insulating material 53 is covered by a vertical lining plate 71 having a lower horizontal outwardly 35 turned flange 12 which is spaced from the flange 19 located at the lower edge of the back plate 18. A second sheet metal plate 73, of the form shown in Fig. 3, is connected to the upper portions of the plate 71 through an intervening bar 40 and spacer 74. The sheet metal plate 73 has a downturned flange 73a at its upper edge. This flange 73a is spaced from the flange 23 by a strip 13b but is located in the same groove. An emulsion of water-proof character is located in the 45 groove between the spaced flanges. This emulsion hardens after a short time and thus a tight seal is formed. Within the door frame described is a metal frame 75 of angular cross section, the upper and lower sides of which bear respectively 50 against the lower and upper sides of the two door frame members 69.

Sliding doors 76, to pass one by the other, are mounted in the frame 75. The flanges 41, 48 and the lip 49 at the rear edge of the upper outer 55 plate 42 extend into a groove in the lower side of the upper wood frame member 69. Similarly, a terminal flange extending from the flange 63 also extends into the groove. A sealing emulsion self-hardening, is packed between these short, upwardly extending flanges. The top frame member 75 is welded to the abutting faces of panel members. Likewise the bottom frame member is welded onto the flange 22 and the 60 upper portion of the plate 73. The side frame members are welded to the vertical flange of the respective side members 39a.

The lower door opening in the rear of the casing has a metal frame 75a therein covering the 65 space between the flanges 19 and 72 and the edges of the flange 21 and the plate 51. As shown, screws extend through the metal frame 75a to hold it in place.

Swinging doors 76a are hinged to the panels 75 70 and the vertical posts 35 of the wood frame

at said openings, are latched to the metal panel 39, as shown in Fig. 2.

The doors 76a preferably are of a structure shown in Figs. 12 and 13. There is provided a rectangular wood frame having vertical sides 5 71 and horizontal upper and lower sides 78, each of the vertical sides 71 having a slot 79 in its outer face near both its upper and lower ends. Associated with such corners of the frame is a metallic clip 80, a flange of which passes under 10 the lower bar 78, and above the upper bar 78 and with a lip 81 entering the slot 79. A screw 82 is used to connect the parts together making a rigid reinforced corner at each of the corners of the frame. Within the frame is a block of 15 heat insulating material 83 similar to all of the rest used, and at the front of the wood frame is a second frame 84 of wood the outer surfaces of which are in the same plane with the insulating material 83. The whole is covered with sheet 20 metal front and rear coverings 85 and 86.

At the upper edge of the front section 51 of the heat insulating material used is a bar 87 the upper side of which parallels the lower outer side portion of the bar 67 previously described. The 25 flange 16 with the terminal lip 17 connects at the upper side with the rear portion of said bar 87 which bar is doubly grooved to receive the downturned lip 17 and one of the flanges of the Z-bar 88. Both of these grooves are filled with 30 liquid rubber latex which is of the non-hardening kind.

As shown in Fig. 19, each of the flanges of the end members is received within the doubly grooved frame member 150. A Z-shaped bar 151 35 has one of its flanges located in the other groove and its other flange, having a lip thereon, is located adjacent the inner edge of the frame member 89. The end liner 59 is fastened to the member 89 as shown. Within the open space, the 40 upper and lower sides of which are provided by the coverings to the bar 87 and the covering to the lower side of the bar 67, the ends of which are provided by the coverings to the members 150, a glass carrying frame is mounted. This 45 frame (Fig. 11) includes upper and lower parallel rails 89 connected by end bars 90, all of the members 89 and 90 of the frame having an inwardly extended ledge 91 at their rear portions.

A rear plate of glass 93 has its outer edge and 50 extreme outer portion of its sides smeared or painted with a rubber mastic or equivalent compound. This plate of glass is then inserted against the ledges 91, these ledges extending inwardly from all of the frame members. Spacer 55 members 94, preferably of channel form bear against one portion of the mastic as shown. The pressure of the channel member 94 against the mastic causes it to spread evenly between the plate glass 93 and the channel and some surplus 60 of the mastic 99 is squeezed inwardly.

At this point in the assemblage the surplus or excess mastic is cleaned from the plate of glass 93 inasmuch as it is readily accessible. Next, a felt filler 95 is positioned alongside of the channel 65 94, see Fig. 11, and then a second plate of glass 96 is inserted as shown. This plate of glass 96 having liquid mastic composition 97 placed thereon. Another channel member 94 is then placed with one of its flanges contacting 70 the mastic 97 and this contact squeezes a surplus inwardly from between the channel and the glass plate 96. Again, this surplus is readily wiped off inasmuch as it is accessible. The felt strip 95 is not accessible at this point in the assem- 75

blage of the device but obviously this is immaterial.

Another felt strip 95 is placed adjacent the other leg of the second channel 94 and the third plate of glass 98 is treated with rubber mastic 97 similarly to the treatment accorded the glass member 96. Following this the bars 99 are securely attached and hold the several members in position. The above construction is very advantageous inasmuch as it provides a seal between each glass plate and an adjacent channel member, this seal being absolutely air tight due to the use of mastic composition of extremely fluid characteristics, this fluid being applied under some pressure whereby all air bubbles or the like are expelled. This construction is only possible due to the novel method of installation whereby the surplus liquid mastic may be cleaned from the interior portions of the plates of glass 93, 96 and 98, and the front side near the edges of the plate glass 96. A second spacer 94 of identical form bears against the inwardly extended leg of the member 97. A second felt 95 is brought against the front panel of the last mentioned spacer 94 and a front plate glass 98 similarly equipped with an L-shaped member 97 of like material bears against the second mentioned felt 95. The parts are all held and clamped in place by bars 99 screwed or otherwise permanently secured at the outer faces of the frame bars 89 and 90, all as fully shown in Fig. 11.

The assembly of the glass plates 93, 96 and 98 with the frame is done in a room from which substantially all the water vapor in the air has been removed, so that the air between the glass plates contains substantially no moisture or vapor to condense and collect on the surfaces of the glass within the spaces between the several plates. With the assembly the glass and frame structure carrying the same at the front upper portion of the refrigerator case, the case structure of the refrigerator is complete.

Within the refrigerator casing the structure of which has been described are supports for a shelf. These supports are L-shaped bars 100 attached at the front and rear and at the inner sides of the case at substantially the plane of the lower upper bar 34 of the wood frame described. On the horizontal inwardly extended legs an open shelf 101 is located which is positioned immediately above the horizontal pipes of a lower refrigerating coil 102 which extends between the ends of the case. A filler 103 of sheet metal extends from the front supporting rail 100, being connected with the lining 58 through an intermediate spacer bar as shown in Fig. 3 the upper edge of the filler member having a welded connection to the Z-bar 88.

In the uppermost portion of the case and extending lengthwise thereof is an upper refrigerating coil 104 comprising several longitudinal pipes between and connected to which are a plurality of spaced apart transverse vanes in the form of flat plates 105. Because of the low temperature within the case when in operation, yet the temperature not being low enough that any condensation on the pipes freezes and becomes solid, such condensation in the form of water will drip from the several refrigerating coils 102 and 104 and the plates 105. I have provided means for collecting the water which thus drips so as to carry it to the lower end of the refrigerator and drain therefrom.

Referring to Figs. 3, 5, 6 and 7 below the upper coils 104 is a longitudinal drip collecting pan

having sides 106 of the form shown which have inner edge portions bent upwardly and extending toward each other but spaced apart as shown at 107. The drip pan has ends 108 and at one end there is a continuous bottom across the pan of short length terminating in an upturned lip 109 (Fig. 6). The bottom of the drip pan between this lip and the adjacent end 108 has an outlet at 110. The inner walls of the drip pan are lined with a plastic material which is resistant to the passage of heat, whereby the walls of the pan are not unduly cooled so as to collect moisture which would drip from the outer sides of said pan.

The pan at its lower side has an elongated opening of a width equal to the distance between the edges of the terminal sections 107. Extending longitudinally a short distance above and over the opening is a flat board 111 which is supported by a sheet metal member 112 having 20 downwardly and outwardly inclined upper sections terminating in U-shaped bends 113 which pass underneath the edges of the board 111. This sheet metal member 112 extends the full length of the board 111. Metallic clips 114 of substantially channel form (Fig. 7) and of relatively short length are located over the metal supporting member 112, the flanges or legs of the channel bearing against the said supporting member. A bolt 115 passes through each of the clips through the metal member 112 and through the board 111 (Fig. 6). Suspending bolts 116, two being shown in Fig. 7 are connected with the top of the case, passed downwardly through the coils, and through the clips 114 whereby the entire structure is suspended within the drip pan described, it being understood that there are supporting rods 116 at each end.

The top of the sheet metal 112 is protected and insulated similarly to the interior of the trough members 106. This insulated material consists of ground cork mixed with emulsified asphalt. It is spread on with a gun which builds up its thickness at approximately $\frac{1}{4}$ ". Thus 45 the member 112 is insulated from the temperature of the relatively cold condensate which drips thereon and moisture does not form underneath the same.

The moisture which condenses on the refrigerating coils and drips down to the pan either falls directly into the pan or against the downwardly and outwardly inclined upper surfaces of the members 112 and is led therefrom outwardly so as to necessarily fall into the pan and not through the opening between the flanges 107. The condensed moisture in the form of water then flows to and out of the outlet 110 being led therefrom through a vertical conduit pipe 117 to a lower drip pan structure which is located 60 underneath the lower refrigerating coil 102.

As clearly shown in Fig. 4 of the drawings and indicated by the arrows therein the air flows upwardly alongside of the glass unit in the front of the case and also alongside of the doors at 65 the rear of the case. This is due to the fact that the layer of air adjacent these sides gradually becomes warmed and this warm air flows upwardly toward the upper cooling unit. The upper cooling unit cools this air whereon it flows 70 downwardly between the trough members 106 and then, after some downward movement, contacts the intermediate coil whereon it flows downwardly through the same and then laterally towards the sides of the case. Here again the air 75

becomes slightly warmer due to heat loss inwardly through the walls and then the air starts its upward journey to repeat the cycle just described. Thus I obtain a cycle of air flow which 5 maintains the refrigerator casing at substantially the same temperature throughout.

The moisture or condensation collecting structure or pan located immediately below the lower refrigerating coils 102 comprises two members 10 one disposed above the other. They extend from the rear to the front being downwardly inclined toward the front end. They are supported by L-shaped bars 118 and 119 at their rear ends and by other bars 122 and 123 at their rear as 15 shown in Fig. 3. The bar 123 is of a substantially U-shape with one leg shorter than the other, and the bar 122 is of substantially Z-shape with one flange shorter than the other, as shown. The bars 118 and 119 are connected by 20 suitable screws or otherwise to vertical posts of wood 120, the lower ends of which are reduced in cross section so as to be received in suitable socket members 121 attached at the rear portion of the refrigerator case. The bars 122 and 25 123 are similarly supported at the front portion of the case. The bar 123 which has been described as of a substantially U-shaped form is closed at one end by a lip 124 (Fig. 10) and in the bottom thereof adjacent the lip is an outlet 30 nipple 125, through which water may flow to the vertical pipe 126 which leads to the bottom of the refrigerator so that the water is delivered onto the bottom inner metal lining 55 of the refrigerator. The bars 122 and 123 and likewise 35 the bars 118 and 119 may be provided with spacing members 127 extending upwardly so as to space various sections of the drip tray construction from each other. In the form illustrated there are two sections in each the upper 40 and lower parts of the drip tray structure, and of course there might be a greater number of sections if desired.

The drip tray and draining structure which is carried by the lower bars 118 and 123 comprises 45 a series of parallel channel bars 128 having upwardly extending flanges (Figs. 3 and 9). These are connected in properly spaced relation to transverse flat bars 129 (Fig. 8). The structure which extends between and is supported by the 50 upper bars 119 and 122 comprises a series of channels 130 with downwardly extending flanges, all except the bars at the ends which are of Z-form as shown at 131 (Fig. 9). These bars are connected together in parallel spaced apart 55 relation by being securely welded to transverse bars 132 as shown in Fig. 8. The downwardly extending flanges of the channel bars 113 and of the Z bars 113 lie over and are located between the planes of the upwardly extending 60 flanges of the lower channels 128 (Fig. 9). With this structure any moisture which drips from the lower refrigerating coils 102 falls either directly into the channels 128 or upon channels 65 130, being then led therefrom to the sides of the channels and thence down the depending flanges thereof so that all moisture eventually reaches the lower channels 128 and is carried downwardly therefrom to the bars 123, emptying 70 into the channel thereof from which it flows through the outlet 125 and the pipe 126. The liquid (water) collected in the upper pan and delivered through the pipe 117 is delivered to the Z-bar 131 and cannot flow to the right because 75 stopped by the upwardly extending flange of the

Z bar but must flow to the left and be thence carried to one of the lower channels 128.

With this structure all moisture condensed upon the refrigerating coils within the casing is carried eventually to the pipe 126 and to the 5 bottom of the refrigerator from which there may be an outlet drain as indicated at 126a to the outside.

It is desirable that the refrigerator casing at its front sides, ends and top at least shall be 10 covered with suitable sheet metal panels to enhance the appearance and cover evidences of the spot welding or other welding used in securing the sheet metal parts together. One form of such covering is shown in Figs. 14, 15 and 16. At the 15 front corners and on the rear corners of the refrigerator case, clip members 135 are attached as shown in Figs. 14 and 16. At the ends of the construction, locking strips 135a, having similar cross sectional shape to the clip members 135, 20 are rigidly attached, the offset portions of these strip members extending beyond the corners of the construction.

A panel member 136, of artistic decoration, has 25 its vertically positioned ends return bent to U-shape as indicated by numeral 138. Thus, this front member 136 is slidably downwardly onto the clips 135. Thus, it is detachably mounted upon the front of the refrigerator construction and may be replaced whenever desired. 30

An end panel 137 is formed to conform to the shape of the end of the refrigerator case and is likewise formed with return bent portions of U-shape, designated 138a these extending upwardly along its sides. Thus, this member is 35 likewise detachably mounted upon the end of the case by downward sliding movement. As shown in Fig. 16, the panels 136 and 137 contact each other at their vertically positioned edges to form a neat appearing juncture. 40

The lower edge of the panel 136 is offset so as to contact the frame of the refrigerator case as clearly shown in Fig. 17. The end panel 137 is likewise similarly offset. Thus a channel shaped recess is formed around the base of the refrigerator. A decorative strip 133, see Figs. 14 and 17, is detachably mounted in this channel. This strip can be easily removed whereby it will not be damaged during the placing of the refrigerator in the desired position. 50

Referring now to Figs. 14 and 15, numeral 140 indicates a locking strip of the shape shown, this strip being fastened along the angularly extending side portions of the front panel. A decorative strip or molding 140, bent to U-shape at 55 both of its edges, at 138c, may be slid downwardly to conceal this portion of the cabinet with an ornamental and detachable strip.

A decorative top panel 141, conforms to the exterior of the top member of the refrigerator 60 cabinet, this panel being placed over the upper ends of the panels 137 and 140 and fastened in position by means of screws. This completes the exterior decorative panel assembly.

By this structure a particularly attractive appearance is provided and all evidence of projection, welding and the like is covered and disguised. 65

Referring now to Fig. 18 wherein is shown a modification of my invention, it will be seen that 70 the inner lining 73 extends upwardly, as indicated at 160 and is then return bent and terminates in a flange 161. The outer member 18 likewise extends upwardly as indicated at 162 and is likewise return bent to form a flange 163. 75

The flanges 161 and 163 are positioned apart by a strip 164. An emulsion, of self-hardening composition surrounds the strip 164 and flanges 161 and 163.

- 5 A border strip 165 conceals the emulsion and the structure adjacent thereto and provides a bearing surface along which the sliding windows 76 operate. The U-shaped portions 160 and 162 form ledges for the sliding windows 76.
- 10 Referring to Fig. 3, it is to be noted that the light bulbs are so positioned as to permit the withdrawal of the unitary glass panel from the refrigerator case. The screws holding the unit frame 89 in place are removed and then the bottom edge of the frame is pulled or pried outwardly. Next, the unit frame is slid downwardly. Inasmuch as the frame is sealed in position by liquid sealing means does not harden no difficulty is encountered in either removing or replacing this unit.
- 15 As shown in Figs. 4 and 14, the top panels are perforated to permit upward passage of the heated air from the electric lights.

The invention described provides a very practical, serviceable and efficient refrigerator structure which has proven exceptionally useful in service and which can be manufactured at a very low cost. The invention is defined in the appended claims and it is to be considered comprehensive of all forms of structure coming within their scope.

I claim:

1. A refrigerator construction comprising a front panel having an inwardly extending flange at its lower edge; said flange terminating in an upstruck portion, and end panels connected to each end of the front panel, each having inwardly extending flanges therearound, a portion of the flange on each member terminating in an extended L-shaped portion and a rear wall structure likewise having an inturned flange at its lower edge, said flange terminating in an upstruck portion, movable closure means located above the rear wall structure and extending upwardly to the top of the construction, a top construction and a transparent front member located between the top and the upper edge of the front panel supported on said L-shaped portions and a bottom member having its opposite sides turned downwardly to form supporting flanges, the width of the bottom member being such as to position the flanges within the upwardly facing channels formed interiorly of the lower side edges of the construction.
- 40 2. A refrigerator consisting of a front panel member having an inwardly extending flange at its lower edge and a second inwardly extending flange at its upper edge, end members having a vertical body and inwardly extending flanges en-

tirely therearound, a portion of said flange on each end member terminating in a downwardly extending L-shaped element, said end members receiving the ends of the front panel member, a lower rear panel member having a flange extending inwardly at its lower edge, an upper rear panel member, a wooden frame construction mounted adjacent the rear panel members, doors mounted upon said wooden frame member, a top extending between the end members, a glass unit located between the top member and the upper flange of the front panel member and closure means located between the top member and the upper rear panel member.

5 3. A combination of elements as set forth in claim 2 in which an additional steel shell is detachably supported in spaced relationship exteriorly of the several panel members.

10 4. In a refrigerator frame construction of box-like shape, the combination of, a first strip, having an offset terminal edge, means for fastening this strip to one face of the refrigerator adjacent a corner with the offset edge spaced from and extending away from the corner juncture, a second strip of offset construction fastened adjacent to the said corner with its terminal edge in non-protruding relationship to the adjacent side of the refrigerator, a concealing panel having a U-shaped terminal edge adapted to have the flange thereof extend into the space between the offset portion of the second mentioned strip and the adjacent side of the refrigerator, a second concealing panel having a U-shaped terminal edge with a flange extending between the offset part of the first strip and the bight portion of the first mentioned concealing plate.

15 5. A construction comprising a sheet metal front panel having an inturned flange at its lower edge and a second flange at its upper edge, sheet metal end members having inturned peripheral flanges, said front panel fitting within the flanges of the end members against the inner sides of the flanges, a sheet metal bottom member having downturned flanges contacting the lower flanges of the ends and the lower flange 20 of the front panel, a rear lower metal member extending between the lower portions of the ends, a rear sheet metal panel member spaced upwardly from the rear lower member, wooden frame means adjacent the rear lower member and the rear sheet metal panel, closure means, including doors, closing the space between the rear members, a top member, sliding doors between the top member and the upper edge of the rear sheet metal panel, and a removable glass 25 unit between the top member and the upper edge of the front panel.

30 JAMES H. WARD, JR.
